UNITED STATES PATENT OFFICE.

ARTHUR J. MASON, OF WEST HARTFORD, CONNECTICUT, ASSIGNOR TO THE M. & S. MANUFACTURING COMPANY, OF HARTFORD, CONNECTICUT, A CORPORATION OF CONNECTICUT.

RECORDING GOLF TALLY.

Application filed July 31, 1923. Serial No. 654,817.

To all whom it may concern:

Be it known that I, ARTHUR J. MASON, a citizen of the United States, residing at West Hartford, in the county of Hartford 5 and State of Connecticut, have invented a new and useful Improvement in Recording Golf Tallies, of which the following is a specification.

This invention relates to those devices 10 which are designed for the purpose of enabling a player to keep a permanent record of his score for each hole of a golf game. The object of the invention is to provide 15 a simple, small, inexpensive, conveniently carried and easily manipulated device into which a dial having localities for recording the several strokes of the different holes may be readily inserted and following each stroke marked so that it will plainly show, 20 when removed, the number of strokes taken for each hole.

In attaining this object in the embodiment of the invention illustrated there is a frame with a record receiving disk having 25 stations representing the different holes, and a recording dial having stations representing the several strokes, the disk being rotatably mounted on an axis which will bring the hole stations in succession 30 back of the dial, and the dial being rotatable on an axis which will carry the recording means with which the dial is provided around the center of the particular hole station back of it, whereby if after each 35 stroke the dial is turned one step and pressed and after each hole the disk is turned one step the dial will have impressed on it the number of strokes played for each hole.

In the accompanying drawings Figure 1 40 shows on enlarged scale a plan of a recording golf tally which embodies the invention. Fig. 2 shows a top edge view of the same. Fig. 3 shows a side edge view with the record disk cut in diametrical section.

The frame which is shown is stamped to 45 shape from sheet metal and folded over to provide a back 1 and a spring arm 2 in front of the back. The frame may be provided with any suitable means for attaching 50 it to the person, clothing or apparatus of

the player. In the device illustrated the back near the edges is pressed out so as to form loops 3 adapted to receive straps which may be fastened about the wrist of the player. Near the middle and punched 55 in from the back is a central hub 4 which is designed to form a pivot for the record disk 5, and punched in from the back near the top is a hub 6 which is adapted to provide an index for locating the record disk 60 as it is turned from station to station. A portion of the frame may be struck inward from the arm or another piece may be attached to the back and bent over the front to provide spring fingers 7 which are designed 65 to press on the top of the record disk and temporarily retain it in position when the disk is thrust under the fingers and pivoted on the central hub.

The record disk has a central perforation 70 8 adapted to fit the central hub on the back of the frame and it has annularly arranged perforations which are desirably numbered in sequence from 1 to 9. The radial distance of these outer perforations from the 75 central perforation is equal to the radial distance of the hub 6 from the central hub 4 so that as the disk is turned from station to station the hub 6 will enter a perforation and retain the disk in position. 80 Annularly arranged around each of the outer perforations are indices which may or may not be numbered. On the dial shown there are twenty of these indices about each perforation which perforations represent the 85 hole stations. If there are nine of these annularly located perforations or stations in the disk they are desirably numbered on one side from 1 to 9 for the first nine holes of the links, and on the other side from 10 to 18 for the second nine holes, the disk being reversed for in and out play.

Pivotaly mounted on the inside of the spring arm which forms the front of the frame is a dial 10 which bears numerals 90 designed to represent the number of strokes. The dial is mounted on the arm with its axis adapted to coincide with the centers of the annularly arranged perforations in the disk. With this arrangement the disk 100

2

may be rotated to bring in succession under the dial each hole perforation in the disk, and the dial may be rotated over the perforations under it. The edge of the dial 5 is preferably notched so that it may be easily gripped for turning and the tip 11 of the arm is bent down so as to form a pawl which will engage with the notches and index the dial after it is turned. The dial 10 shown has twenty notches and these notches are numbered consecutively. In the dial is a perforation 12 through which one of the hole numerals on the face of the disk below is visible. Near the top the arm has 15 a perforation 13 through which one of the numerals of the dial is visible. Projecting inward from the back of the dial a short distance from the dial pivot is a prick punch 14.

20 The dial is set to show zero through the perforation in the arm, and the disk is thrust under the spring fingers over the pivot hub and set to show 1 through the perforation in the dial. After each stroke 25 the dial is turned one notch and then pressed inward. This forms a series of impressions or marks in a circle about the first hole perforation in the disk, which impressions of course will equal the number of strokes 30 made for that hole. After each hole is played the dial is turned back to zero and the disk turned to bring the next hole station below the dial. This is repeated until 35 nine holes have been played and then the disk may be withdrawn and replaced the other side up for receiving the registrations for the next nine holes.

With this device operated in this manner a permanent record may be made showing 40 the exact number of strokes for each hole of a game, the strokes for each hole being located around the corresponding hole in the disk.

The invention claimed is:—

- 45 1. A recording golf tally comprising a frame, a disk detachably applied to and rotatable on the frame, a dial rotatably mounted on the frame and movable toward and from the disk, the axis of the dial being eccentric to the axis of the disk, and means 50 carried by the dial and adapted to be revolved over and impinged against the disk.
- 55 2. A recording golf tally comprising a frame, a disk detachably applied to and rotatable on the frame, said disk having anularly arranged and consecutively numbered perforations, a dial rotatably mounted on the frame and movable toward and from the disk, the axis of the dial being eccentric 60 to the axis of the disk, and means carried by the dial and adapted to be impinged against the disk around the perforations therein.
- 65 3. A recording golf tally comprising a frame bent to provide a back and a spring

arm in front of the back, a disk detachably applied to and rotatable on the back of the frame, a dial rotatably mounted on said spring arm, the axis of the dial being eccentric to the axis of the disk, and means 70 carried by the dial and adapted to be revolved over and impinged against the disk.

4. A recording golf tally comprising a frame having a back, a spring arm and spring finger, a disk rotatably mounted on 75 the frame and detachably held thereto by the spring finger, a dial rotatably mounted on the said arm and movable toward and from the disk, the axis of the dial being eccentric to the axis of the disk, and means 80 carried by the dial and adapted to be revolved over and impinged against the disk.

5. A recording golf tally comprising a frame having a back and a spring arm, a disk detachably applied to and rotatable on 85 the frame, a dial with a notched edge rotatably mounted on the spring arm, said arm having a part engaged with the notched edge of the dial, the axis of the dial being eccentric to the axis of the disk, and means 90 carried by the dial and adapted to be revolved over and impinged against the disk.

6. A recording golf tally comprising a frame, a disk detachably applied to and rotatable on the frame, said disk having anularly arranged and consecutively numbered perforations with indices about said perforations, a dial rotatably mounted on the frame and movable toward and from the disk, the axis of the dial being eccentric 100 to the axis of the disk, and means carried by the dial and adapted to be impinged against the disk and mark said indices.

7. A recording golf tally comprising a frame having a back and a spring arm, a disk detachably applied to and rotatable on 105 the frame, a dial with a notched edge, said notches being consecutively numbered and said dial being rotatably mounted on the spring arm with its axis eccentric to the axis of the disk, and means carried by the dial and adapted to be revolved over and impinged against the disk.

8. A recording golf tally comprising a frame having a back, a spring arm and spring finger, a disk rotatably mounted on the frame and detachably held thereto by the spring finger, a dial rotatably mounted on the said arm with its axis eccentric to the axis of the disk, and a prick punch carried 115 by the dial and adapted to be revolved over and impinged against the disk.

9. A recording golf tally comprising a frame bent to provide a back and a spring arm and spring finger in front of the back, said back being punched to provide a pivot hub and an index hub, a perforated disk rotatably held on said pivot hub by said 120 spring finger and adapted to be indexed by said index hub, a dial rotatably mounted on 125 said index hub, a dial rotatably mounted on 130

said spring arm with its axis eccentric to the axis of the disk, and means carried by the dial and adapted to be revolved over and impinged against the disk.

5 10. A recording golf tally comprising a frame, a disk with numbered hole stations, detachably applied to and rotatable on the

frame, a dial with numbered stroke stations, rotatably mounted on the frame, the axis of the dial being eccentric to the axis of 10 the disk, and means carried by the dial and adapted to be impinged against the disk.

ARTHUR J. MASON.
